UNITED STATES PATENT OFFICE.

AUGUST W. OFELDT, OF NEWARK, NEW JERSEY, ASSIGNOR, BY MESNE ASSIGNMENTS, TO MAX PFLUG, OF NEWARK, NEW JERSEY.

ENGINE.

SPECIFICATION forming part of Letters Patent No. 742,481, dated October 27, 1903.

Application filed March 30, 1901. Serial No. 53,691. (No model.)

To all whom it may concern:

Be it known that I, AUGUST W. OFELDT, a citizen of the United States, residing at Newark, in the county of Essex and State of New Jersey, have invented certain new and useful Improvements in Engines; and I do hereby declare the following to be a full, clear, and exact description of the invention, such as will enable others skilled in the art to which it appertains to make and use the same.

My invention relates to improvements in steam and other fluid-pressure engines; and it consists in the novel construction of the engine.

The objects of my invention are to improve and simplify the construction of steam and other fluid-pressure engines, and particularly of small high-speed compound engines, such as are used on steam-launches and automobiles, to render the same more compact, to reduce the wear of the parts, and generally to make the engine as simple, compact, efficient, and durable as possible. These objects are attained in the invention herein described, and illustrated in the drawings which accompany and form a part of this specification, in which—

Figure 1 is a central vertical section through the high-pressure and low-pressure cylinders of the engine, the view being taken on the irregular section-line X X of Fig. 2. Fig. 2 is a horizontal section of the engine through the center line of the high-pressure cylinders. Fig. 3 is a detail cross-section of one of the low-pressure cylinders, showing the exhaust-port thereof. Fig. 4 is an elevation of the engine with the valve-chest cover sectioned. Fig. 5 is a section of the engine along the center line of the low-pressure cylinders. Fig. 6 is a detail view showing the clamping device employed for holding together the sections of the locking-ring, and Fig. 7 is a detail view showing the swivel-head on the end of the operating-shaft.

In this engine there are two high-pressure cylinders and two low-pressure cylinders, arranged in the form of a cross, with like cylinders opposite each other. In each cylinder there is a piston, and the connecting-rods of these pistons are connected to the same crank-pin. The engine is provided with a valve-

chamber adjacent to the cylinders, which contains the valves of the engine and an eccentric for operating them and likewise serves as a receiver-chamber. The high-pressure valves are piston-valves, and the high-pressure steam-chests are formed in the cover of the valve-chamber.

Referring now to the drawings, numerals 11 designate the high-pressure cylinders, and 22 the pistons thereof.

33 designate the low-pressure cylinders, and 44 the pistons thereof.

5 designates a crank-shaft mounted in bearings in the engine-casing, and 6 and 7 designate crank-arms, and 8 a crank-pin. The engine-casing is provided with a circular boss or projection 9, within which the crank-arm 6 revolves, and said boss is provided with a stuffing-box 10, surrounding the shaft 5.

Numerals 1111 designate the high-pressure connecting-rods and numerals 1212 the low-pressure connecting-rods. The pistons are trunk-pistons, the connecting-rods being connected to their several pistons by pivot-pins 13. The bores of the pistons in which these pivot-pins are located register with the grooves which receive the piston-rings 14, and the pivot-pins are held in place within their bores by set-screws. The connecting-rods are provided at their inner ends with laterally-projecting bosses, which are embraced by the two-part locking-ring 15. Each of these bosses embraces a small portion only of the circumference of the crank-pin 8; but this is not objectionable, since the cylinders are all single-acting, and therefore the thrust of the connecting-rods against the crank-pin is always in one direction. The ring 15 merely holds the ends of the connecting-rods in proper position.

16 is a valve-chamber and receiver-space, and 17 is a cover therefor arranged to be bolted to the cylinder-casting. In the cover 17 are cylindrical high-pressure steam-chests 18 and also guide-cylinders 19 for the cross-heads of the high-pressure valves. Each high-pressure valve comprises double or balanced valve-pistons 20, working within their steam-chests 18, a guiding-head or cross-head 21, working within its guide-cylinder 19, a stem 22, connecting these parts, and a lug 23, carrying a

pin 24, working in the groove of a grooved eccentric 25 and provided with a friction-roll. These friction-rollers have a slight clearance in the groove of the eccentric 25.

5 The low-pressure valves are designated by numerals 26. They are D-valves working on valve-seats formed on the cylinder-casting and driven from the grooved eccentric 25 in the same manner as the high-pressure valves.

10 Stop-pins 27, bearing lightly against the backs of these valves, are provided to prevent them from lifting off from their seats when the engine is not under steam. The low-pressure valves are guided by contact with the sides

15 of the pockets in the cover 17, in which they work. This is illustrated in Fig. 4, in which figure one of the low-pressure valves is shown in position in its pocket.

Steam is admitted to the high-pressure 20 steam-chest 18 by means of pipes 28. Ports 29, adapted to be closed by the valve-pistons 20, serve each to convey live steam to its high-pressure cylinder when the corresponding valve is in one position and to convey ex-

25 haust-steam from such cylinder to the main portion of the valve-chamber 16 when said valve is in the opposite position. The outer end of each steam-chest 18 is connected with the receiver-space 16 by a small passage, so

30 that steam leaking past the valve may not collect and condense in the end of the steam-chest.

Numerals 30 designate ports connecting the low-pressure cylinders and the receiver-chamber 16.

35 Numerals 31 designate exhaust-ports covered by the low-pressure valves.

Each valve 26 is adapted alternately to permit steam from the receiver-space to enter

40 its cylinder 3 and to permit exhaust from said cylinder to pass through ports 30 and 31 and thence from the engine.

The crank-arm 7 is provided with a journal-boss 32, mounted in a stuffing-box bearing in that wall of the cylinder-casting which separates the crank-chamber from the receiver-space. This journal-boss is hollow and is adapted to receive a bushing 33, surrounding an operating-shaft 34. This bush-

45 ing is, in fact, a nut, being provided with an internal screw-thread intermeshing with a corresponding screw-thread on the shaft 34. Said shaft 34 passes through a stuffing-box in the cover-plate 17 and is provided at its

50 end with a swiveled head 35, adapted to be connected to any convenient operating device, such as a lever. The grooved eccentric 25 is mounted upon the shaft 34 and may overlap the journal-boss 32 of crank-arm 7,

55 as shown, and is provided with a key 36, Fig. 5, working within a keyway 37, Fig. 2, of shaft 34. Screw-bushing 33 is keyed within the boss of crank 7, but fits loosely upon the shaft 34. Therefore if shaft 34 be pulled

60 outward or pushed inward by means of its swiveled head it will be caused to rotate with respect to the crank-shaft and in rotating

will rotate the eccentric 25 with reference to the crank-shaft. By this means the engine may be reversed or the points of admission and cut-off to the several cylinders changed at will. Bushing 33 is in function a part of the boss 32 of crank-arm 7 and is formed separately therefrom for convenience only. These parts are formed most conveniently by turning the thread upon the operating-shaft 34, placing it in a mold and casting the bushing 33 about it, said bushing being formed, preferably, of gun-metal or similar material, then hammering the bushing until it is loose upon the shaft 34, and finally turning it down to a drive fit with the socket in crank 7.

The method of holding together the sections of the locking-ring 15 is shown in Fig. 85 6. The ends of the sections of this ring interlock, and through each pair of interlocking ends there is a bore adapted to receive a taper locking-pin 38, which screws into one section of the ring and is also provided with a lock-nut. By screwing up the pin 38 the sections of the ring 15 may be drawn together as tightly as necessary. As will be seen in the drawings, the high-pressure cylinders are offset toward the valve-chamber relatively 95 to the low-pressure cylinders. This makes it possible to provide connecting-rods with laterally-projecting lugs of sufficient length to permit the use of a locking-ring 15 of sufficient width to hold the connecting-rods firmly 100 and yet enables the connecting-rods to be very nearly central in their cylinders.

The engine may be assembled readily through the opening in the casing of the crank-chamber normally closed by the flange 39 of the stuffing-box 10.

While I have described my engine as a steam-engine, it is obvious that it may be used with other working fluids, such as air or naphtha-gas.

I do not limit myself to the use of any particular number of cylinders or to the use of piston-valves for the high-pressure cylinders or to the use of flat valves for the low-pressure cylinders.

The engine is capable of many modifications in construction and arrangement of the parts, and I do not limit myself to the particular details of construction and arrangement herein shown and described.

Having thus completely described my invention, what I claim, and desire to secure by Letters Patent, is—

1. In a compound engine, the combination, with an engine-casing including high-pressure and low-pressure cylinders arranged in different angular positions about a common crank-shaft, and a crank-case and a combined valve-chamber and receiver-space, separate from said crank-case; of a crank-shaft, pistons, connecting-rods, high-pressure and low-pressure valves within said valve-chamber, the former arranged to pass the high-pressure exhaust into the said valve-chamber,

means for admitting working fluid to the engine, and means for operating said valves.

2. In a compound engine, the combination, with an engine-casing including high-pressure and low-pressure cylinders arranged in different angular positions about a common crank-shaft, and a crank-case and a combined valve-chamber and receiver-space, separate from said crank-case; of a crank-shaft, pistons, connecting-rods, high-pressure and low-pressure valves within said valve-chamber, the former arranged to pass the high-pressure exhaust into the said valve-chamber, means for admitting working fluid to the engine, and valve-operating means arranged to operate said valves and provided with means whereby the engine may be reversed.

3. In a compound engine, the combination, with an engine-casing including high-pressure and low-pressure cylinders arranged in different angular positions about a common crank-shaft, and a crank-case and a combined valve-chamber and receiver-space, separate from said crank-case; of a crank-shaft, pistons, connecting-rods, high-pressure and low-pressure valves within said valve-chamber, the former arranged to pass the high-pressure exhaust into the said valve-chamber, means for admitting working fluid to the engine, and an eccentric driven by the crank-shaft, arranged to operate said valves.

4. In a compound engine, the combination, with an engine-casing including high-pressure and low-pressure cylinders arranged in different angular positions about a common crank-shaft, and a crank-case and a combined valve-chamber and receiver-space separate from said crank-case, of a crank-shaft, pistons, connecting-rods, high-pressure and low-pressure valves within said valve-chamber, the former arranged to pass the high-pressure exhaust into the said valve-chamber, means for admitting working fluid to the engine, an eccentric driven by said crank-shaft arranged to operate said valves, and means for shifting said eccentric with respect to said shaft.

5. In a compound engine, the combination, with an engine-casing including high-pressure and low-pressure cylinders arranged in different angular positions about a common crank-shaft, and a crank-case and a combined valve-chamber and receiver-space separate from said crank-case, of a crank-shaft, pistons, connecting-rods, high-pressure and low-pressure valves within said valve-chamber, the former arranged to pass the high-pressure exhaust into the said valve-chamber, means for admitting working fluid to the engine, and a grooved eccentric driven by said shaft, said valves being provided with projections fitting within said groove, whereby said valves may be operated by said eccentric.

6. In a compound engine, the combination, with an engine-casing including high-pressure and low-pressure cylinders arranged in different angular positions about a common

crank-shaft, and a crank-case and a combined valve-chamber and receiver-space separate from said crank-case, of a crank-shaft, pistons, connecting-rods, high-pressure and low-pressure valves within said valve-chamber, the former arranged to pass the high-pressure exhaust into the said valve-chamber, means for admitting working fluid to the engine, a grooved eccentric driven by said shaft, said valves being provided with projections fitting within said groove, whereby said valve may be operated by said eccentric, and means for shifting said eccentric with reference to said shaft.

7. In a compound engine, the combination, with an engine-casing including high-pressure and low-pressure cylinders arranged in different angular positions about a common crank-shaft, and a crank-case and a combined valve-chamber and receiver-space separate from said crank-case, of pistons, connecting-rods, high-pressure and low-pressure valves within said valve-chamber, the former arranged to pass the high-pressure exhaust into the said valve-chamber, means for admitting working fluid to the engine, a crank-shaft terminating at one end within the engine-casing, such end of the shaft being hollow, and being provided with a spiral thread, an operating-rod mounted in such hollow end and having a corresponding and intermeshing thread, and an eccentric adapted to operate said valves, and mounted upon said operating-rod and having a spined connection therewith, whereby longitudinal movement of said rod shifts the eccentric.

8. In a compound engine, the combination, with an engine-casing including high-pressure and low-pressure cylinders arranged in different angular positions about a common crank-shaft, said casing including likewise a removable valve-chamber cover inclosing a combined valve-chamber and receiver-space, of a crank-shaft, pistons, connecting-rods, high-pressure and low-pressure valves, the former arranged to pass the high-pressure exhaust into the said valve-chamber, means for admitting working fluid to the engine, and means for operating said valves.

9. In a compound engine, the combination, with an engine-casing having high-pressure and low-pressure cylinders arranged in different angular positions about a common crank-shaft, and a valve-chamber cover secured to the cylinders and inclosing therewith a combined valve-chamber and receiver-space, of high-pressure and low-pressure valves, located within said chamber, the former arranged to pass the high-pressure exhaust into said chamber, means for admitting working fluid to the engine, and means for operating said valves.

10. In a compound engine, the combination, with an engine-casing having high-pressure and low-pressure cylinders arranged in different angular positions about a common crank-shaft, and a valve-chamber cover inclosing

with said cylinders a combined valve-chamber and receiver-space, of a crank-shaft, pistons, connecting-rods, high-pressure and low-pressure valves, the former of the piston type 5 and mounted in the valve-chamber cover, means for admitting working fluid to the engine, and means for operating said valves.

11. In a compound engine, the combination, with an engine-casing having high-pressure 10 and low-pressure cylinders arranged in different angular positions about a common crank-shaft, and a removable valve-chamber cover inclosing with said cylinders a combined 15 valve-chamber and receiver-space, of a crank-shaft, pistons, connecting-rods, high-pressure and low-pressure valves, the former arranged to pass the high-pressure exhaust into the said valve-chamber, and the latter being flat valves, working against the cylinder-face, 20 and suitably guided, means for admitting working fluid to the engine, and means for operating said valves.

12. In a compound engine, the combination, with an engine-casing having high-pressure 25 and low-pressure cylinders arranged in different angular positions about a common crank-shaft, and a removable valve-chamber cover inclosing with said cylinders a combined 30 valve-chamber and receiver-space, of a crank-shaft, pistons, connecting-rods, high-pressure and low-pressure valves, the former arranged to pass the high-pressure exhaust into the said valve-chamber, and the latter being flat valves, working in and guided by 35 pockets formed in the valve-chamber cover, means for admitting working fluid to the engine, and means for operating said valves.

13. In a compound engine, the combination, with an engine-casing having high-pressure 40 and low-pressure cylinders arranged in different angular positions about a common crank-shaft, and a removable valve-chamber cover inclosing with said cylinders a combined 45 valve-chamber and receiver-space, and having formed in it a high-pressure steam-chest and a pocket in which a low-pressure valve may work, of a crank-shaft, pistons, connecting-rods, high-pressure and low-pressure valves, the former arranged to pass the high-

pressure exhaust into the said valve-chamber, 50 means for admitting working fluid to the engine, and means for operating said valves.

14. In a compound engine, the combination, with an engine-casing including high-pressure and low-pressure cylinders arranged in 5 different angular positions about a common crank-shaft, and a valve-chamber adjacent to said cylinders, the high-pressure cylinder being offset toward the valve-chamber, relatively to the low-pressure cylinder, of a crank-shaft, pistons, connecting-rods, adapted to be connected to a common crank-pin on said shaft, each of said connecting-rods being provided with a crank-pin-bearing surface which does not completely surround said pin, and 60 being provided with a projecting lug adapted to receive a locking-ring by which the several connecting-rods may be secured to said crank-pin, the said lugs being located on the adjacent sides of the high-pressure and low-pressure connecting-rods, and a sectional locking-ring, located between the high-pressure and low-pressure connecting-rods, and adapted to secure the connecting-rods to the crank-pin. 65

15. In an engine, the combination, with cylinders arranged in different angular positions about a common crank-shaft, a crank-shaft, pistons, connecting-rods therefor adapted to be connected to a common crank-pin on said 80 shaft, each of said connecting-rods being provided with a crank-pin-bearing surface which does not completely surround said pin, and being provided also with a projecting lug adapted to receive a locking-ring by which 85 the several connecting-rods may be secured to said crank-pin, a sectional locking-ring, the sections of which are secured together at one end and at the other end are provided with interlocking tongues and registering apertures, 90 and a taper key parallel with the crank-pin for holding said sections together. 75

In testimony whereof I affix my signature in the presence of two witnesses.

AUGUST W. OFELDT.
